GOVERNOR

John W. Ryan, Bel Air, Manning Citron, Los Angeles, and Berne Danielson, Pacific Palisades, Calif., assignors to Mattel, Inc., Hawthorne, Calif., a corporation of California

Filed Dec. 12, 1963, Ser. No. 330,114
5 Claims. (Cl. 188—184)

In general, the present invention relates to a centrifugal governor. More particularly, the present invention relates to an inexpensive, easily constructed centrifugal governor adapted to eliminate vibration therein irrespective of the orientation or acceleration of the governor.

Most centrifugal governors have independently operating weights each with its own spring for biasing it inwardly. Such arrangement operates satisfactorily when the plane of rotation of the governor is horizontal, but when the rotation is in a vertical direction, vibration occurs. Such problem is due to the unequal forces on the weights since the upper weight has the force of gravity urging the weight inwardly while the lower weight has the force of gravity urging it outwardly. A similar effect occurs when the governor is subjected to an accelerating force such as when it is thrown. The vibration problem associated with the random positioning of the governor interferes with the proper functioning of the governor in applications such as the voice unit used in talking dolls such as the one described in U.S. Patent No. 3,095,201. Because of the governor vibration, the quality of sound reproduction in such voice unit is greatly affected.

In addition, where two biased springs are utilized in centrifugal governors, a careful balancing of spring tension is necessary to assure that no unbalanced forces are acting on the governor. As mentioned above, such unbalance of forces adversely affects the proper functioning of the governor in uses such as doll voice units.

In view of the foregoing state of the prior art, one of the objects of the present invention is a centrifugal governor which is adapted to eliminate vibration therein irrespective of the orientation or acceleration of the governor.

Another object of the present invention is a centrifugal governor which utilizes a single spring means for biasing weights inwardly.

Still another object of the present invention is an inexpensive, easily constructed centrifugal governor which is adapted to be used in doll voice units.

Other objects and advantages of the present invention will be readily apparent from the following description and drawings which illustrate a preferred exemplary embodiment of the present invention.

In general, the present invention involves a centrifugal governor having a rotatably mounted rotor and two weights rotatably mounted on said rotor. Between the weights is an interlocking means for equalizing the forces exerted thereon and a spring means for biasing the weights inwardly.

In order to facilitate understanding of the present invention, reference will now be made to the appended drawings of a preferred specific embodiment of the present invention. Such drawings should not be construed as limiting the invention which is properly set forth in the appended claims.

In the drawings:

FIGURE 1 is a plan view of a doll voice unit showing the governor of the present invention installed therein.

FIGURE 2 is an enlarged cross-sectional view of FIGURE 1 taken along the lines 2—2 of FIGURE 1.

2

FIGURE 3 is a cross-sectional view of FIGURE 2 taken along the lines 3—3 of FIGURE 2.

FIGURE 4 is an exploded perspective view of the governor of the present invention.

5 As illustrated in FIGS. 1—4, the governor 10 of the present invention includes a stationary housing 11, a rotor 20 rotatably mounted within the housing 11, two weights 40 and 50 rotatably mounted on the rotor 11, interlocking means 60 between the weights 40 and 50 and spring means 70 operatively connected between the weights 40 and 50.

The housing 11 (shown in outline in FIGS. 2 and 3) includes an upper wall 12 and lower wall 13 with a circular side wall 14. The rotor 20 includes a central shaft 21 journaled at its first end 22 in the upper wall 12 of the housing 11 and journaled at its second end 23 in a support 24 shown in outline in FIG. 2. About the second end 23 of the shaft 21 is formed a gear 25 which meshes with a timing or gear belt 26 and is thereby operatively connected with the remainder of the voice unit. The shaft 21 extends through an aperture 15 in the lower wall 13 of the housing 11 and is mounted therein by means of a washer 16 and a sleeve 17. The second end 23 of the shaft 21 has a cap 18 thereon for positioning the timing belt 26 and reducing the friction with the support 24. Adjacent the first end 22 of the shaft 21 is a cross-bar 27 which has its ends 28 and 29 extending radially adjacent to the housing 11. Each end 28 and 29 has a socket 30 and 31, respectively, formed therein.

Rotatably mounted on the rotor 20 are two weights 40 and 50. The weights 40 and 50 each have a post 41 and 51, respectively, which is slidably mounted in the sockets 31 and 30, respectively, of the cross-bar 27 so that the weight is rotatable inwardly and outwardly with respect to the rotor 20. Adjacent the posts 41 and 51 of the weights 40 and 50, respectively, are arcuate-shaped lugs 42 and 52, respectively. The lugs 42 and 52 have friction means 43 and 53, respectively, thereon adapted to engage the inner surface 19 of the side wall 14 of the housing 11 when the weights 40 and 50 move outwardly. The friction means 43 and 53 may consist simply of pads of felt adhesively connected to the lugs 42 and 52, respectively.

Between the weights 40 and 50 are interlocking means 60 for equalizing the forces exerted thereon. The interlocking means 60 include opposing gear sectors 61 and 62 on the weights 40 and 50, respectively. The interlocking means 60 also include an idler arm 63 rotatably mounted on the rotor 20 between the weights 40 and 50. The idler arm 63 has two gear sectors 64 and 65 which are meshed with the adjoining weight gear sectors 61 and 62, respectively.

Extending between the rotor 20 and the idler arm 63 is a spring means 70 for biasing the weights 40 and 50 inwardly. The spring means 70 includes a torsion spring 71 mounted on the rotor 20 and with one end 72 braced against the end 29 of the cross-bar 27 of the rotor 20 and the other end 73 braced against a boss 66 on the idler arm 60.

60 When the voice unit is not in use, the spring means 70 moves the weights 40 and 50 inwardly adjacent to the rotor 20. However, when the voice unit is operated, the gear belt 26 causes the rotor 20 and the weights 40 and 50 connected thereto to rotate. The rotation of the weights 40 and 50 imparts a centrifugal force which overcomes the bias of the spring means 70 so that the weights 40 and 50 move outwardly until the friction means 43 and 53 thereon contact the side wall 14 of the housing 11. The frictional engagement between the housing 11 and friction means 43 and 53 acts on the weights 40 and 50 to govern the speed of the voice unit.

When the governor 10 is oriented so that the weights

40 and 50 rotate in a vertical plane, the force of gravity will tend to cause an unbalance with respect to the forces exerted by the weights 40 and 50 on the housing 11. However, since the weights 40 and 50 are interlocked through their gear sector and the respective gear sectors of the idler arm 63, the result is such force is equalized so that no unbalance force is exerted against the housing 11. Consequently, no vibration is caused.

Many other specific embodiments of the present invention will be obvious to one skilled in the art in view of this disclosure. For example, three or four weights may be utilized instead of the two weights illustrated in the preferred embodiment. Also, although the centrifugal governor is utilized within a housing so that the weights frictionally contact the walls of the housing, the same arrangement may be used without the housing. In addition, any convenient means may be used to interlock the weights of the governor so long as it functions to equalize the forces exerted thereon.

There are many features in the present invention which clearly show the significant advance the present invention presents over the prior art. Consequently, only a few of the more outstanding features will be pointed out to illustrate the unexpected and unusual results attained by the present invention. One feature of the present invention is the use of an interlocking means to equalize the force exerted on the weights of the centrifugal governor. Thus, irrespective of the orientation of the governor or the acceleration to which it is subjected, the force of gravity on the weights is compensated for and no vibration results therefrom. Another feature of the present invention is the utilization of a single spring for biasing the weights inwardly. Thus, a careful balancing of the spring tension is rendered unnecessary and assembly of the governor is simplified.

It will be understood that the foregoing description and examples are only illustrative of the present invention, and it is not intended that the invention be limited thereto. All substitutions, alterations and modifications of the present invention which come within the scope of the following claims or to which the present invention is readily susceptible without departing from the spirit and scope of this disclosure are considered part of the present invention.

It is claimed:

1. An inexpensive, easily constructed centrifugal governor adapted to eliminate vibration therein irrespective of the orientation or acceleration of the governor, comprising:

- (a) a stationary housing;
- (b) a rotor rotatably mounted within said housing;
- (c) two weights rotatably mounted on said rotor, said weights each having a gear sector and friction means thereon adapted to engage the inner surface of said housing when said weight moves outwardly;
- (d) an idler arm rotatably mounted on said rotor between said weights, said idler arm having two gear sectors with each gear sector being meshed with the adjoining weight gear sector; and
- (e) a spring means extending between said rotor and idler arm for biasing said weights inwardly.

2. An inexpensive, easily constructed centrifugal governor adapted to eliminate vibration therein irrespective of the orientation or acceleration of the governor, comprising:

- (a) a stationary housing;
- (b) a rotor rotatably mounted within said housing,

said rotor having a cross-bar with the ends of said cross-bar extending radially adjacent to said housing;

- (c) two weights rotatably mounted on said rotor, said weights each having a gear sector and friction means thereon adapted to engage the inner surface of said housing when said weights move outwardly, each of said weights being rotatably mounted on an end of said cross-bar;

- (d) an idler arm rotatably mounted on said rotor between said weights, said idler arm having two gear sectors with each gear sector being meshed with the adjoining weight gear sector; and

- (e) a spring means extending between said rotor and said idler arm for biasing said weights inwardly.

3. An inexpensive, easily constructed centrifugal governor adapted to eliminate vibration therein irrespective of the orientation or acceleration of the governor, comprising:

- (a) a stationary housing;
- (b) a rotor rotatably mounted within said housing;
- (c) two weights rotatably mounted on said rotor, said weights each having a gear sector and friction means thereon adapted to engage the inner surface of said housing when said weights move outwardly;

- (d) an idler arm rotatably mounted on said rotor between said weights, said idler arm having two gear sectors with each gear sector being meshed with the adjoining weight gear sector; and

- (e) a spring means extending between said rotor and said idler arm for biasing said weights inwardly, said spring means comprising a torsion spring mounted on said rotor with one end braced against said rotor and the other end braced against said idler arm.

4. An inexpensive, easily constructed centrifugal governor adapted to eliminate vibration therein irrespective of the orientation or acceleration of the governor, comprising:

- (a) a rotatably mounted rotor;
- (b) two weights rotatably mounted on said rotor;
- (c) interlocking means between said weights for equalizing the forces exerted thereon, said interlocking means including gear sectors on each of said weights and an idler arm rotatably mounted on said rotor between said weights, said idler arm having two gear sectors with each gear sector being meshed with the adjoining weight gear sector; and

- (d) a spring means operatively connected between said weights for biasing said weights inwardly.

5. An inexpensive, easily constructed centrifugal governor adapted to eliminate vibration therein irrespective of the orientation or acceleration of the governor, comprising:

- (a) a rotatably mounted rotor;
- (b) two weights rotatably mounted on said rotor;
- (c) idler means interlocking said weights for equalizing the forces exerted thereon; and

- (d) spring means connecting said idler means to said rotor for biasing said weights inwardly.
